UNITED STATES PATENT OFFICE.

EPFA H. RYON, OF PASADENA, CALIFORNIA, ASSIGNOR TO CROMPTON & KNOWLES LOOM WORKS, OF WORCESTER, MASSACHUSETTS, A CORPORATION OF MASSACHUSETTS.

WEFT DETECTOR FOR LOOM TRANSFERRER ARMS.

Application filed October 1, 1926. Serial No. 138,965.

This invention relates to improvements in weft detectors for weft replenishing looms wherein the detector is mounted on a regularly moving transerrer arm and it is the 5 principal object of the invention to simplify the construction of the parts movable relatively to the transerrer arm to the end that they may be assembled as a unit and then mounted on the arm.

10 My previous Patent No. 1,372,316, shows a transerrer arm which is given a regular downward movement on detecting beats of the loom to cooperate with the filling in the shuttle under the magazine. A plunger 15 slidably mounted with respect to the transerrer arm is normally held in retracted non-indicating position, but at the time of transfer is moved outwardly to cooperate on the upward stroke of the transerrer arm with 20 a rocking indicating lever operatively connected to the magazine. In the various forms in which this general construction has been embodied the plunger has usually been supported directly by and mounted to slide 25 on the transerrer arm, being retained by some form of latch or detent, the holding effect of which is overcome by a detector mounted on a lever pivoted on the transerrer arm. In such constructions it is usually necessary to adjust the various parts to 30 function properly after they have been assembled on the transerrer arm. It is an important object of my present invention to mount the indicating plunger on the lever 35 which supports the detector and to dispense with the latch or detent heretofore employed. In this way I am enabled to assemble all the operating parts of the device independent of the transerrer arm and then attach 40 them directly to the arm at one point.

In detectors of the type specified the part which does the detecting is lower than usual on the indicating beat so as to require more time to be withdrawn from the shuttle than 45 is the case on non-indicating detecting beats of the loom. It is a further object of my invention so to relate the parts that the co-action between the indicating plunger and the indicating lever on the replenishing 50 mechanism will act to lift the detector away from the shuttle at the first part of the upward stroke of the transerrer, in this way insuring proper and complete removal of the

detector on detecting beats to avoid interference with the front wall of the shuttle 55 as the lay moves rearwardly.

In my aforesaid patent the lever on which the detector is mounted cooperates with a yielding actuator supported independently 60 of the transerrer arm and in the form of the invention shown in co-pending application Ser. No. 127,694, filed by Turner the yielding actuator is dispensed with and the energizing force necessary to give the detector its detecting movement is derived 65 from the energy stored in the supporting lever when the transerrer arm comes to rest. The detector set forth herein may be actuated by either of these methods but I choose to illustrate the same in connection 70 with the latter or inertia actuated type.

With these and other objects in view which will appear as the description proceeds, my invention resides in the combination and arrangement of parts hereinafter 75 described and set forth in the claims.

In the accompanying drawings wherein I have shown a convenient form of my invention,

Fig. 1 is a central longitudinal section 80 through that part of the transerrer arm which lies parallel to the lay, the parts being shown in the position they assume when detecting a full bobbin,

Fig. 2 is a view similar to Fig. 1 but 85 showing the parts moved to indicating position, the detector cooperating with a substantially exhausted bobbin,

Fig. 3 is a view similar to Fig. 1 but showing the parts in full lines in the normal position they assume with respect to the transerrer arm and showing said parts in dotted lines in one of the positions they assume on the upward stroke of the transerrer immediately following indication of weft exhaustion, and

Fig. 4 is a detail vertical section on line 4-4 of Fig. 3.

Referring more particularly to the drawings it will be seen that I have provided a 100 transerrer arm 10 having a portion 11 extending parallel to the lay and located above the shuttle box (not shown). Said portion 11 is provided with a heel 12 which engages the butt B of a bobbin W. By means of 105 mechanism not shown but fully set forth

in the aforesaid patent the portion 11 of the transerrer arm is moved downwardly toward the bobbin on alternate or detecting beats of the loom when the supply of weft 5 is thereunder. An indicating lever 13 mounted to move about a pivot (not shown) rocks at the time of indication of weft exhaustion to initiate replenishment of the depleted shuttle.

10 In carrying my invention into effect I provide a supporting lever 20 having pivotally mounted at one end thereof as at 21 a weft detector 22 having a roughened detecting surface 23. An indicating element 15 shown as a plunger 24 has a head 25 which fits loosely through the bore 26 of the lever 20, and said plunger has a shoulder 27 against which presses a compression spring 28 the left end of which bears against a depending forked guide 29 formed as part of the lever 20. Said guide is shown more particularly in Fig. 4 as having a pair of walls 30 spaced to define a slot 31 through which extends the left and flattened end 32 of the 25 plunger. Said end 32 is further provided with a notch 33 to cooperate with a retaining plate 34 held to the walls 30 by means of screws 35.

30 The lever 20 is pivoted on a pin 36 secured to the transerrer arm and extending through a vertical slot 37 in which the lever moves. A tension spring 38 extends between a horn 39 on the detector and an upstanding finger 40 on the transerrer arm 35 and serves normally to hold the parts in the position shown in Fig. 3 with respect to the transerrer arm.

35 The detector has a locking arm 41 adapted for cooperation with the tip 42 of end 32 40 and said detector is further provided with a tripping knee 43 so placed as to engage the underside of the plunger end 32 along a preferably inclined surface 44 at the time of indication of weft exhaustion. The 45 spring 38 normally holds the lever 20 against the bottom of finger 40 to position said lever and parts carried thereby.

40 In operation the notch 33 is held by the plate 34 as indicated in Fig. 1, the head 25 50 in this position being out of the path of the cam lever 13 and the spring 38 holding the detecting surface 23 in proper position by engagement of the left end of the locking arm 41 with the tip 42 of the plunger. 55 As the transerrer arm arrives at its lowermost position the energy stored in lever 20 will move the same downwardly until the teeth 23 engage the yarn and if sufficient weft for continued weaving is present the 60 detector will be held against angular motion about pivot 21 as shown in Fig. 1. When weft is substantially exhausted, however, as shown in Fig. 2, the teeth 23 will be unrestrained and will move to the right, 65 the knee 43 of the detector engaging the

lower inclined surface 44 of the plunger end 32 to raise the notch 33 above retaining plate 34. Spring 28 will immediately act to move the plunger to the position shown in Fig. 2, cotter pin 45 limiting such movement by contact with a portion of the lever 20. It will be seen that when the detector moves to the position shown in Fig. 2 the locking arm 41 moves from plunger locking position and permits the adjacent end of the 70 plunger to move upwardly to be released. 75

As soon as the parts assume the position shown in Fig. 2 the transerrer arm will move upwardly and the extended head 25 will engage the cam lever 13 to rock the 80 same in the manner set forth in the aforesaid patent. Because of the fact that the plunger moves pivotally about pin 36 the first contact of the plunger with the indicating lever will serve to raise the supporting lever 20 and detector from the position shown in Fig. 2, to that shown in Fig. 3, causing said detector to rise quickly out of the path of the parts moving rearwardly with the lay. As the transerrer arm continues its upward 85 movement the head 25 will engage an inclined surface 46 on the indicating lever 13 to move the plunger to the left until notch 33 lies over the left hand end of the retaining plate 34, at which time spring 38 acting through the locking arm 41 of the detector will depress the head 32 so as to insure holding engagement between the notch and the plate. Spring 38 and arm 41 will thereafter constitute a yielding lock to prevent 90 accidental upward movement of the plunger. 95

From the foregoing it will be seen that I have provided a detector for a loom transerrer arm wherein the detecting element and the indicating plunger are both mounted on a lever which has a single fixed point of connection with the transerrer arm, thereby permitting the assembly of these devices away from the transerrer arm with resultant manufacturing advantages. It will further be seen that the first action of the indicating lever 13 is to raise the detector 22 so that the same will be out of the shuttle, thus preventing improper contact between the front wall of the shuttle and any part of the detecting mechanism. Furthermore, it will be seen that the single spring which serves to raise the supporting lever acts also to lock the plunger in retracted position, thus preventing accidental indication of weft exhaustion, this result being achieved without the use of a latch or other movable device directly connected to the transerrer arm. Also, the single spring serves to return the detector and supporting lever therefor to normal position, as has been the case in previous motions of this type and furthermore serves to lock the plunger yielding against accidental release. 100 105 110 115 120 125 130

Having thus described my invention it

will be apparent that changes and modifications may be made therein by those skilled in the art without departing from the spirit and scope of the invention, and I do not wish to be limited to the details herein disclosed, but what I claim is:

1. In a weft detector for a loom having a transerrer arm moved toward the surface to be detected on detecting beats of the loom and an indicating lever, a weft detector, an indicating plunger to cooperate with the lever and to be operatively related to the detector to indicate weft exhaustion and normally in non-indicating position relatively to the lever, and a common support for said detector and indicating plunger movably mounted with respect to the transerrer arm and movable relatively to the transerrer arm to present the detector to the surface to be detected.

2. In a weft detector for a loom having a transerrer arm moved toward the surface to be detected on detecting beats of the loom and an indicating lever, a weft detector, an indicating plunger to cooperate with the lever and to be operatively related to the detector to indicate weft exhaustion, and a common support for said detector and indicating plunger pivotally mounted with respect to the transerrer arm and movable relatively to the transerrer arm to present the detector to the surface to be detected.

3. In a weft detector for a loom having a transerrer arm moved toward the surface to be detected on detecting beats of the loom, a supporting lever pivotally mounted on the transerrer arm, a weft detector pivotally supported on the lever, and an indicating plunger slidably mounted on the supporting lever and lying in the path of the detector to be operatively engaged thereby for all positions of the supporting lever at the time of indication of weft exhaustion.

4. In a weft detector for a loom having a transerrer arm moved toward the surface to be detected on detecting beats of the loom, a supporting lever pivoted to the transerrer arm, an indicating plunger supported by and mounted for sliding movement with respect to the lever, means to hold the indicating plunger in retracted non-indicating position on the lever, and a weft detector supported by the lever and movable at the time of weft exhaustion into engagement with the indicating plunger to move the latter out of retracted position with respect to the supporting lever.

5. In a weft detector for a loom having a transerrer arm moved toward the surface to be detected on detecting beats of the loom and an indicating lever, a weft detector, an indicating plunger to cooperate with the lever and to be operatively engaged thereby, and a supporting lever pivoted to the transerrer arm, said detector and plunger mount-

ed on the lever and moving with the latter about the pivot of the lever.

6. In a weft detector for a loom having a transerrer arm moved toward the surface to be detected on detecting beats of the loom and an indicating lever, a weft detector, an indicating plunger to cooperate with the lever and to be operatively engaged thereby, a supporting lever pivoted to the transerrer arm, said detector and plunger mounted on the lever and moving with the latter about the pivot of the lever, and resilient means interposed between the detector and a part of the transerrer arm to hold said detector, lever, and plunger in normal raised position, said detector, plunger, and lever moving as a unit toward the surface to be detected against the action of the resilient means about the point of attachment to the transerrer arm.

7. In a weft detector for a loom having a transerrer arm moved toward the surface to be detected on detecting beats of the loom and an indicating lever, a weft detector, an indicating plunger to cooperate with the lever and to cooperate therewith, and a common support for said detector and plunger movable relatively to the transerrer arm.

8. In a weft detector for a loom having a transerrer arm moved toward the surface to be detected on detecting beats of the loom and an indicating lever, a weft detector, an indicating plunger to cooperate with the lever and to cooperate therewith, a common support for said detector and plunger movable relatively to the transerrer arm, and means to move the indicating plunger relatively to the support and transerrer arm when engaged by the detector on an indicating beat of the loom.

9. In a weft detector for a loom having a transerrer arm moved toward the surface to be detected on detecting beats of the loom, said transerrer arm receiving an upward movement immediately after being moved toward the surface to be detected, a weft detector, an indicating element normally retracted in non-indicating position and engaged by the detector, a common support for the weft detector and indicating element, means to move the indicating element relatively to the support when said indicating element is engaged by the weft detector on an indicating beat of the loom, and an indicating lever to be engaged by the indicating element when the latter is in indicating position on the upward movement of the transerrer arm to raise the detector.

10. In a weft detector for a loom having a transerrer arm moved toward the surface to be detected on detecting beats of the loom, said transerrer arm receiving an upward movement immediately after being moved toward the surface to be detected, a weft detector movably mounted with respect to the transerrer arm, an indicating element oper-

- atively related to the weft detector and movable at indication of weft exhaustion relatively to the transerrer arm, means engaged by the indicating element on the upward stroke of the transerrer arm, and a connection between the weft detector and the indicating element to cause said weft detector to be raised by engagement between the indicating element and said means.
- 10 11. In a weft detector for a loom having a transerrer arm moved toward the surface to be detected on detecting beats of the loom, a weft detector, an indicating element engaged thereby, a common support for the detector and element, cooperating means formed between the support and the indicating element to hold the latter normally in retracted non-indicating position, and cooperating means formed on the detector and indicating element to hold the latter in locked position when the detector is in normal non-indicating position.
- 15 12. In a weft detector for a loom having a transerrer arm moved toward the surface to be detected on detecting beats of the loom, a weft detector, an indicating element to be engaged thereby at indication of weft exhaustion, a common support for the detector and indicating element movable relatively to the transerrer arm, and means formed on

the indicating element and support to hold said element normally in non-indicating position, said detector and element normally having direct contact with each other to lock the latter against accidental movement toward indicating position. 35

13. In a weft detector for a loom having a transerrer arm moved toward the surface to be detected on detecting beats of the loom, a weft detector, an indicating element normally held in non-indicating position and engageable by the detector at indication of weft exhaustion and movable to indicating position when so engaged by the detector, means moving with the detector to engage a 40 part of the indicating element, a common support for the detector and indicating element movable with respect to the transerrer arm, and resilient means interposed between the detector and the transerrer arm, said resilient means normally restoring the detector to detecting position and acting to move the common support to normal position and acting also to hold said means movable with the detector yieldingly against the indicating element to yieldingly lock the latter in 45 non-indicating position. 50

55 In testimony whereof I have hereunto affixed my signature.

EPPA H. RYON.
